ELECTRIC SWITCH

Filed Dec. 11, 1926

UNITED STATES PATENT OFFICE

HARRY A. DOUGLAS, OF BRONSON, MICHIGAN

ELECTRIC SWITCH

Application filed December 11, 1926. Serial No. 154,229.

My invention relates to motor vehicles and to switching mechanism which, in its preferred embodiment, is particularly adapted for employment upon motor vehicles for governing the stop lights or other signaling devices thereon.

The invention has for its objects the provision of means for rendering dust-proof the switching mechanism enclosing casing. 10 In carrying out this object of my invention, I employ a dust-proof packing at the opening in the casing through which opening an operating member projects to the exterior of the casing to be operable outside of the 15 casing. This packing surrounds the projecting portion of the switch operating member and is pressed upon by an inner portion of this operating member. Spring means are desirably employed for pressing the inner 20 portion of the operating member upon the packing and to press the packing, in turn, upon the inner face of the casing wall where the packing is disposed. One of the contacts of the switching mechanism is desirably 25 spring pressed and presses the inner operating member portion upon the packing.

The invention has for another object the provision of a mounting arm for the switching mechanism which is also a structural addition to the casing to cooperate therewith in assembling the casing and parts within the casing. In carrying out this object of my invention, the mounting arm is held in assembly with the casing wall that surrounds 35 the contacts of the switching mechanism by clinching formations provided upon said casing wall. In accordance with one of the features of the invention, this arm has a cup formation which receives said casing wall 40 and the base member of insulation surrounded by this wall and carrying a contact or contacts of the switching mechanism and in which cup said base member is desirably seated.

45 The invention will be more fully explained in connection with the accompanying drawing in which Fig. 1 is a view, somewhat diagrammatic, illustrating a portion of the body of an automobile in longitudinal section, one 50 of the rear propelling vehicle wheels and

braking mechanism which is preferably employed to control the switching mechanism; Fig. 2 is a view in elevation of the switching mechanism and portions of the parts adjacent thereto; Fig. 3 is a sectional view on line 3—3 of Fig. 2; Fig. 4 is a sectional view on line 4—4 of Fig. 3; Fig. 5 is a reverse view of the switching mechanism and parts as illustrated in Fig. 2; Fig. 6 is a sectional view on line 6—6 of Fig. 3; and Fig. 7 is a perspective view of the circuit controlling member of the switch.

The switching mechanism shown employs a generally cylindrical casing 1 having a front end wall 2 which is formed with an annular cavity, bulging outwardly, which receives a dust-proof packing or gasket 3 which may be of fibrous material saturated with lubricant. The front wall of the casing is formed with an opening through which the hub portion 4 of a switch operating member projects to the exterior of the casing where it may be operated, as by means of an arm 5 riveted thereto, as indicated at 6, the edge of the opening in the wall 2 being coaxial with the casing wall 1 whereby the switch operating member is turned upon an axis that is coincident with the axis of said casing end wall. The hub portion 4 of the switch operating member is preferably formed of sheet metal and has a flange portion 7 which is held in snug engagement with the front face of an insulating disc 8 which is coaxial with the hub 4 and casing wall 1, the means for assembling the flange and disc being desirably the prongs 9 which are struck from the flange and are clinched into engagement with the disc, as illustrated in Fig. 7. The disc is formed with three cylindrical recesses 10 extending from the rear face of the disc nearly to the front face thereof and arranged upon a circle that is concentric with the disc. A triangular metallic plate 11 is formed with three circular openings upon the same circle with the recesses 10. Spring barrels 12 are passed through these openings in plate 11, these spring barrels being formed with heads 13 at the rear ends thereof, these heads being clamped between the triangular metallic plate 11 and another triangular metallic 100

plate 14. A spring 15 is contained in each spring barrel, these springs pressing upon the plungers 16 that are contained in the spring barrels and project through the front ends thereof, the front ends of these plungers bottoming upon the end walls of the recesses 10. The rear end of the casing is closed by a disc or base member of insulation 17 which carries a metallic contact sleeve 18, this sleeve passing through the disc and being coaxial therewith, the disc being also coaxial with the casing wall 1, the disc 8 and the hub 4. The disc or base member 17 is held from rotation by means of the feather 1' which enters a slot 17' formed in the part 17.

15 The metallic contact plate 14 is rearwardly bulged, as indicated at 19, to constantly engage the front end of the metallic contact sleeve 18. One of the circuit wires 20 is brought into connection with the sleeve 18 by means of a screw 21 which is threaded into said sleeve. The plate 14 is thus constantly in connection with said wire. The plate 14 has another rearwardly bulging contact formation 22 which is engageable with another contact sleeve 23 formed similarly to the contact sleeve 18 and having connection with another wire 24 by means of a screw 25. The contact 23 is eccentric to the contact 18 and desirably has an extension 23' flush with the inner face of the disc 17. When the arm 5 is turned, the contact 22 is brought into or out of engagement with the contact 23 and when this contact 22 is in open circuit position, it is received in the depression 26 formed upon the inner face of the disc 17. This disc is held in a fixed zone with respect to the casing wall 1, as will hereinafter appear. The springs 15, in addition to holding the contacts 19 and 22 in engagement with the parts complementary thereto, also press the disc 8 forwardly to bring the flange 7, assembled therewith, into tight engagement with the packing 3 whereby the opening through the front casing end wall is thoroughly sealed to guard against the access of dust or other foreign matter.

20 The degree of turning movement of the switch operating members 4, 5, 7, 8 is limited by means of the engaging formation 27 pressed inwardly from the front corner portion of the casing and thus forming a part of the casing, as is preferred, and the engaging formations 28 upon said switch operating member which are desirably provided upon the flange 7 which is preferably formed with an arcuate recess having the formations 28 at its ends, this arcuate recess being of sufficient length to provide the maximum range of movement for said switch operating member.

25 The switching mechanism is shown as being provided with a mounting arm 29 which, as illustrated, is secured to the floor 30 of the vehicle body by means of screws 31 which are passed through the angular upper end of the

arm. The lower end of the upright branch of the supporting arm has a cup formation 32 in which the insulating disc or base member 17 and the rear end of the wall 1 are seated, the circular side wall of the cup partially surrounding the casing wall 1 and this casing wall surrounding the base member 17. The casing wall 1 is desirably formed with tongues 33 which are passed through slots in the bottom of the cup 32 and are thereafter turned inwardly toward the center of the cup whereby the cup is clinched into engagement with said casing wall and the rear face of the base member 17. A circular opening is formed in the bottom of the cup to accommodate the terminals 18 and 23 and the wiring connected therewith.

30 The switch, preferably constructed as above specifically described, is, in accordance with another feature of my invention, suitably assembled with the floor 30 of the vehicle body, as hitherto explained. The lower end of the lever arm 5 is connected by means of a rod 34 with a clamp 35 which is secured to the brake rod 36, in the embodiment of the invention illustrated. The forward end of this brake rod is connected with a foot lever 37 which is moved in one direction by the pressure of the foot to apply the brakes of which one is shown at 38. A suitable spring 39 restores the foot lever when it is released. In the embodiment of the invention illustrated, a stop light 40 is included in a grounded circuit which is opened and closed by the operating members 4, 5, 7, 8 according to the direction of movement of the foot lever 37, the lamp 49 having one terminal grounded and the other terminal connected to the contact 23 through the battery or other source of current 41, the contact 18 being grounded. When the foot lever 37 is depressed, the arm 5 is positively turned, owing to the positive connection thereof with the rod 36, to establish circuit through the lamp 40. When the foot lever is released, the spring 39 restores it to normal and in this restoring movement the arm 5 is positively turned in a reverse direction positively to open the lamp circuit. The connection of the rod 34 with the arm 5 is sufficiently far from the axis of movement 115 of the arm as to secure the proper range of movement of the operating member of the switch in correspondence with the range of movement of the lever 37 and the rod 36.

35 Changes may be made without departing from the invention.

Having thus described my invention, I claim:

1. The combination of a casing having an axial opening in one end, a switch operating member positioned in said opening, a dust proof packing interposed between the operating member and casing, a contact device within the casing controlled by the operating member, said device including a spring con-

tact, and means operated by the reaction of said spring contact from a fixed part within the casing to compress said dust proof packing.

- 5 2. The combination of a casing having an axial opening in one end, a switch operating member positioned in said opening and having a lateral extension overlying the inner face of said casing end, a dust proof packing 10 interposed between said lateral extension and casing end, and cooperating fixed and spring pressed complementary contacts within the casing, the spring pressed contact being carried by the operating member and reacting 15 from a part fixed within the casing to press said operating member outwardly thereby to compress said dust proof packing between the lateral extension of the operating member and the end of the casing.
- 20 3. The combination of a casing having an axial opening in one end, a switch operating member positioned in said opening and having a lateral extension overlying the inner face of said casing end, a dust proof packing 25 interposed between said lateral extension and casing end, and cooperating fixed and spring pressed complementary contacts within the casing, one of which is carried by the operating member, said spring pressed contact re- 30 acting from a fixed part within the casing to press said operating member outwardly thereby to compress said dust proof packing between the lateral extension of the operating member and the end of the casing.
- 35 In witness whereof, I hereunto subscribe my name.

HARRY A. DOUGLAS.
